PRESSURE RESPONSIVE INDICATING
DEVICE

William E. Naylor, Ridgefield Park, N. J., assignor
to Bendix Aviation Corporation, Teterboro,
N. J., a corporation of Delaware

Application October 12, 1945, Serial No. 622,024

1 Claim. (Cl. 177—311)

1

This invention relates to a pressure actuated alarm mechanism; and more particularly to an alarm mechanism for cabin planes, actuated by the varying barometric pressure due to the changes in altitude, to warn the pilot or the plane occupants of the lower and upper altitude limits within which oxygen is required.

An object of this invention is to provide an alarm mechanism in which the expansion and/or contraction of an aneroid will open and close an electrical circuit to set off an alarm.

Another object of the present invention is to provide an alarm of the character described with coarse and fine control contacts, the coarse contacts closing at approximately the present altitude while the fine contacts close at the exact present altitude to complete the alarm circuit.

A further object of my present invention is to provide an alarm mechanism of the character described with a relay actuated alarm circuit having means to hold said circuit energized after the coarse or fine contacts open due to changes in plane altitude, the alarm circuit holding means being rendered inoperative upon actuation of a switch in the relay circuit.

Yet another object of this invention is to provide an alarm mechanism of the character described which shall be corrected for varying temperatures encountered at different flight altitudes.

Still another object of this invention is to provide a highly improved, compact and rugged alarm mechanism of the character described which shall be relatively inexpensive to manufacture, easily installed, positive in action, which shall have a large variety of applications and yet be practical and efficient to a high degree in use.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the appended claim.

In the accompanying drawings, in which one of the various possible illustrative embodiments of this invention is shown,

Figure 1 is a perspective view of a pressure re-

2

sponsive alarm mechanism embodying the invention.

Figure 2 is another perspective view of the alarm mechanism.

Figure 3 is a schematic wiring diagram for the alarm mechanism.

Figure 4 is an enlarged sectional view of a bimetal pivot support, while

Figure 5 is an enlarged sectional view of a second bimetal pivot support.

Referring now in detail to Figures 1 and 2, 10 designates a pressure responsive alarm mechanism embodying the present invention. The mechanism 10 is mounted on two horizontal parts 11 and 12 fixed to each other and spaced apart as by the two spacers 13 and a standard 14. Fixed to the standard 14 by suitable means is a double bellows aneroid 15.

Journalized in a suitable bearing 16 fixed to the bottom plate 12, is a jack shaft 17 extending upwardly and parallel to the two spacers 13; the upper end of said jack shaft extending through a suitable opening (not shown) in the top plate 11. Fixed to the shaft 17 is a hub 18 about which is coiled a centering spring 19. One end of said spring is fixed to said hub while the other end is fixed to a spacer 13, as by screw 20.

To correct the expansion of the aneroid 15 for temperature variations so that the alarm system 30 may function at the proper altitude regardless of temperature changes, the pivots used for interconnecting the aneroid and the shaft 17 are both fixed to suitable bimetal mountings.

Inserted through an enlarged section 21 of shaft 17 is a threaded stud 22 which carries a formed, bimetal strip 23, (Figure 4). Fixed to the turned end of said strip is a bifurcated lug 24 provided with a pivot pin 25. The stud may be moved by turning nut 26 to vary the distance 40 between the center line of the shaft 17 and the pivot pin 25 to permit a finer calibration by changing the angular movement of the shaft. After adjustment, the stud 22 is locked in place by a set screw 27.

Fixed to the center of aneroid 15 is a small plate 28 carrying a horizontal stud 29. Rotatably mounted in a suitable opening in said stud is a bimetal rod 30 (Figure 5). Fixed to the rod and coaxial therewith is a pivot pin 31. The bimetal rod may be rotated to adjust the center line of

the pin 23 to be in direct line with the linear movement of the aneroid upon expansion thereof under all temperature conditions encountered. As indicated in Figure 5 the most suitable position for the bimetal rod is when the line made by the joining of the two metals is approximately 45° from the plane of the face of aneroid 15. In this manner the travel of the pin 23 off the line of aneroid movement is kept at a minimum during temperature changes.

A link 24 pivoted on the pins 67 and 23 interconnects the aneroid 15 and the shaft 17 to oscillate the same upon expansion and contraction of the aneroid due to the barometric pressure changes.

Means is now provided to utilize the oscillation of the shaft 17 to engage and disengage electrical circuit-making elements.

To this end, there is affixed to the top plate 11 adjacent to the upper end of the jack shaft 17, as by screws 28, an insulation block 26 made of suitable insulation material such as Bakelite or nylon. The insulation block 26 is provided with two metal inserts 27 and 28, the end faces of said inserts being flush with the top surface of the insulation block. The two inserts are connected electrically in series by two horizontal binding posts 29 inserted into the block 26 to engage said inserts, and by a wire 30.

Fixed to the upper end of the shaft 17, as by screw 31, is a wiper contact 32 adapted to engage both of said inserts 27 and 28 upon oscillation of said jack shaft. A counter-weight 33 is fixed to said jack shaft 17 between the centering spring and the top plate 11 to counter-balance the weight of the link 24 and wiper arm 32.

Upon expansion of the aneroid 15, shaft 17 will be rotated in a counter-clockwise direction (Figure 1) to move the wiper arm 32 over the metal insert 27, and then over the insert 28. It will be obvious that the spacing of the inserts 27 and 28 will determine the altitude at which the alarm circuit may be actuated. The spacing of the contacts, as shown in Figure 1, approximates a low altitude of 10,250 feet for the insert 27 and 40,500 feet for the insert 28.

Means is now provided to complete an alarm circuit by a vernier mechanism at the exact altitude for which the alarm is set.

To this end there is fixed to the jack shaft 17 a sector gear 35 having its own small counter-weight 36. Journalized in a suitable bracket 37 and through the top plate 11, is a shaft 38 to which is affixed a pinion 39 meshing with the teeth of the sector gear 35. Fixed to the shaft 38 above plate 11, is a small insulation disc 40 provided with a metal insert 41. The insulation disc 40 is provided with two peripheral grooves 42 exposing a minute segment of the metal insert 41.

Fixed to the top plate 11 by a screw 43, is a contact holder 44 made of insulation material and retaining two brushes 45. Brushes 45 are adapted to ride in the peripheral grooves 42 in said disc 40 and engage the exposed segments of the metal insert 41. One of said brushes is connected to the wire 30 interconnecting the two inserts 27 and 28. The other of said brushes is connected to a wire 46.

In the present embodiment of the invention, the relative movement of the disc 40 and the wiper arm 32 is approximately 20 to 1. The movement of the wiper arm 32 may be called the coarse altitude adjustment while the movement of the disc 40 may be called the fine altitude adjustment. The wiper arm 32 will engage the insert 27 at ap-

proximately 10,000 feet, and disengage said insert at approximately 10,500 feet. To eliminate the error in altitude, the fine adjustment disc 40 upon its rotation and engagement of the insert 41 by the brushes 45 will correct the altitude to an exact 10,250 feet. As will hereinafter appear, an alarm circuit will thus be completed at the 10,250 feet altitude preset into the mechanism. The higher altitude insert 28 will operate in the same manner as heretofore described at the 40,500 feet altitude.

Referring now to Figure 3, the wire 46 interconnects one of the brushes 45 with a relay coil 47. The other end of the relay coil 47 is connected by wire 48 to one side of the battery 49, the other side of said battery being connected by wire 50 to the wiper arm 32. The relay coil 47 is provided with two switch arms 51 and 52 interconnected by an insulation block 53. Upon energization of the relay coil 47, switch arm 51 is adapted to engage a stationary contact 54, while switch arm 52 is adapted to engage a stationary contact 55. Switch arm 51 is connected by wire 56 to one side of a push-button switch 57, through said switch and by wire 58 to the wire 50. The stationary contact 54 is connected by wire 59 to the wire 46. Switch arm 52 is connected by wire 60 through an alarm 61, herein disclosed as a bell, to one side of the battery 62, the other side of said battery being connected by wire 63 to the stationary contact 55.

In operation, the relay coil 47 will be energized when the wiper arm 32 engages either of the inserts 27 and 28 and brushes 45 engage insert 41. Upon energization of the relay 47, switch arm 51 will engage the stationary contact 54 to complete a holding circuit for said relay through the push-button switch 57. At the same time, switch arm 52 will engage the stationary contact 55 to complete the electrical circuit for the alarm 61. The relay coil 47 will thus remain energized and actuate the alarm 61 even though the wiper arm 32 disengages either of the inserts 27 or 28; or when the brushes 45 disengage the insert 41. The alarm circuit will remain closed until the push-button switch 57 is opened to break the holding circuit of the relay coil.

It will thus be seen that there is provided a pressure actuated alarm device in which the several objects of this invention are achieved, and which is well adapted to meet the conditions of practical use.

As various possible embodiments might be made of the above invention, and as various changes might be made in the embodiment set forth, it is to be understood that all matters herein set forth, or shown in the accompanying drawings, are to be interpreted as illustrative, and not in a limiting sense.

Having thus described my invention, I claim as new and desire to secure by Letters Patent:

A pressure responsive device comprising, a pressure responsive member adapted to be actuated by varying pressures, a shaft adapted to be oscillated by said member, a wiper arm on said shaft, at least two electrical contacts spaced apart from each other adapted to be engaged by said wiper arm upon movement by said shaft, the spacing of said contacts being representative of different pressure conditions; an insulation disc rotated by said shaft, the angular displacement of said disc being greater than the angular displacement of said shaft by said members; an electrical conducting insert in said disc close to peripheral edge thereof, two peripheral grooves in said disc to expose two segments of said insert, a pair of brushes

cooperating with said grooves adapted to engage simultaneously the exposed segments of said insert, an electrical circuit including said contacts, wiper arm, insert and brushes; a relay coil in said circuit adapted to be energized upon concurrent engagement of at least one of said contacts by said wiper arm and said insert by both of said brushes, and means actuated by the energized relay coil to indicate a pressure condition represented by the contact engaged by said wiper arm.
